UNITED STATES PATENT OFFICE.

EWALD E. STURK, OF PORTLAND, MAINE.

SLED.

Application filed February 24, 1923. Serial No. 620,936.

To all whom it may concern:

Be it known that I, EWALD E. STURK, a citizen of the United States, residing at Portland, in the county of Cumberland and State of Maine, have invented certain new and useful Improvements in a Sled, of which the following is a specification.

The present invention relates generally to sleds and more particularly to that kind used by young folks in coasting.

The principal object of the invention is to provide the sled with braking and guiding means combined whereby the speed and direction of the sled may be easily regulated while used in coasting.

Another important object of the invention is to provide a brake and guiding attachment which is capable of being mounted upon a large class of sleds now commonly in use.

A further object of the invention is to provide a propelling attachment whereby a child seated upon the sled may propel the same and thus the attachment will not only afford amusement but will also give the child considerable exercise.

A still further object of the invention is to generally improve upon braking and guiding attachments for sleds by providing a device which is simple and efficient in construction, reliable in operation, durable, inexpensive to manufacture, easily operated, and well adapted to the purpose for which it is designed.

With the above and numerous other objects in view as will appear as the description progresses, the invention resides in certain novel features of construction, and in the combination and arrangement of parts as will be hereinafter more fully described and claimed.

For the purpose of illustrating my invention, I have shown in the accompanying drawing that form thereof which is at present preferred by me, since the same will give in practice satisfactory and reliable results, although it is to be understood that the various instrumentalities of which my invention consists can be variously arranged and organized and that my invention is not limited to the precise embodiment and organization of these instrumentalities as herein shown and described.

In the drawing—

Figure 1 is a top plan view of a sled 55 embodying my invention,

Figure 2 is a longitudinal vertical section taken therethrough substantially on the line 2—2 of Figure 1,

Figure 3 is a transverse vertical section 60 taken through the sled substantially on the line 3—3 of Figure 2 looking in the direction of the arrow,

Figure 4 is a detail enlarged section of the attachment, 65

Figure 5 is a detail elevation thereof, a portion being shown in section, and

Figures 6 and 7 are detail sections taken substantially on the lines 6—6 and 7—7 respectively of Figure 5. 70

Referring to the drawing in detail it will be seen that the sled which I have illustrated is of conventional construction and includes the runners 1 which are curved at their forward ends as indicated at 2. The longitudinal beams 3 are supported by the forward ends of the runners 1 and also by the standards 4 rising from the runners 1. Cross beams 5 are mounted on the standards 4 and connected to the longitudinal 75 beams 3 and a board 6 is mounted thereon upon which the riders of the sled may seat themselves.

A cross bar 7 is mounted on the beams 3 and spaced forwardly of the board 6. A 80 plate 8 is supported on this cross bar 7 and also on the forward end of the board 6, a block 9 being interposed between the rear end of the plate 8 and the forward end of the board 6 and this block is secured to the 85 board 6 by a strap 10. The board 6 is provided with an opening 11 preferably rectangular in shape and extending longitudinally with the sled. A rod 12 pierces the rectangular opening 11 and is constructed with a pointed lower end having a pointed shoe 13 mounted thereon for engagement with the ground. This rod forms a ground engaging means for braking the sled and also guiding the same and is 90 mounted upon a universal joint bracket so that it may be engaged with the ground at various angles in relation to the sled as is indicated by the dotted lines in Figures 2 and 3. The universal joint bracket 100 includes the oblong loop frame 14 provided

at its ends with trunnions 15 which are in the form of bolts journaled in the cross bar 7 and in the block 9 whereby the loop frame is rotatably mounted. The rod 12 is rotatable and slidabile in this loop frame 14 by having the rods 12 constructed with a longitudinally extending slot or pocket 17 in which is disposed an expansible coil spring 18 connected at its lower end to a bolt 19 disposed transversely of the slot 17 at its lower end and the upper end of this spring is attached to a bolt 20 extending transversely through the slot 17 and piercing the sides of the loop frame 14 so as to be carried thereby. Guide plates 21 are disposed on each side of the rod 12 so as to partially enclose the slot 17 leaving sufficient space therebetween for free longitudinal movement of the bolt 20 in relation to the rod 12. Thus it will be seen that the spring 18 normally holds the rod 12 out of engagement with the ground and that the rod may be pushed downwardly in engagement with the ground at a large variety of angles in relation to the sled. The upper end of the rod 12 has mounted thereon a handle bar 23 attached thereto by the angle braces 24 so that the rider of the sled may regulate the rod 12 while seated upon the board 6. A spring 25 of the expansible coil type is connected to the lower end of the rod 12 and to the body of the sled preferably adjacent the forward cross beam 5 or at any other point to the rear of the rod 12. This spring 25 when in its normal nontensioned or compressed position holds the rod 12 in a vertical position.

The ground engaging means including the rod 12 and its associated parts may be mounted upon a large number of sleds now commonly in use and will prove of great service in properly braking and guiding such sleds and making it possible to swerve to one side or stop abruptly whereby accidents in coasting may be practically eliminated. In the large cities throughout the country it has become very dangerous to coast upon the streets because of the congestion of traffic and even where streets are set aside for this purpose there is always the danger of some vehicle crossing the street through ignorance of the reservation of the street for coasting purposes and this endangers the life of the coasters but with an attachment such as here disclosed the coaster can swerve either to the right or left immediately and if necessary brake the sled very abruptly and thus practically obviate the danger of collision. Furthermore the device may be also used for braking the sled slowly and bringing it to a stop with proper comfort to the occupants of the sled. In operating the device an inspection of the drawing will show that by

disposing the rod 12 as indicated by the line A in figure 2 and pushing the rod 12 downwardly in engagement with the ground the sled may be stopped very abruptly. This use is only contemplated, of course, for emergency purposes. When it is desired to stop the sled slowly and with comfort to the operator the rod 12 is positioned along the line B and engaged with the ground with whatever pressure is desired or found necessary. In using the ground engaging bar for guiding purposes it is moved to the position indicated by dotted lines in Figure 3. Thus if the ground engaging rod 12 is moved to the position C and engaged with the ground by pushing the same downwardly the sled would have a tendency to move to the right and should the rod be moved to the position D and engaged with the ground the sled would have a tendency to move to the left. To demonstrate the device in avoiding a collision with a vehicle crossing the path of the sled I will take as an example a street running north and south and the sled is moving toward the south at a considerable rate of speed and a vehicle crosses the path of the sled going west. In such an emergency it is desirable that the coaster swerve suddenly to the right and this may be done quickly by moving the rod 12 in A position and then in C position and engaging the same with the ground and the sled would swerve suddenly to the right and the worst that could happen would be to dislodge the rider from the sled but this even would be avoided by one skilled in the use of the device.

When using the device for propelling purposes the child seated upon the sled moves the ground engaging element to the position A and then pushes upon the same to the position B thus advancing the sled forwardly and this operation may be reversed for moving the sled backwards. The sled may thus be propelled without the necessity of the child pushing the same by engaging the ground with the feet and wearing out shoes and the like and furthermore the device will afford the child considerable exercise and amusement and is particularly useful in moving the sled up to the edge of a hill down which it is desired to coast. There are other usages to which the device may be put with equal advantage but it is thought that the utility of the invention is clearly demonstrated with the few examples herewith given.

Having thus described my invention what I claim as new is:—

1. In combination, a sled, a loop frame revolvably mounted on the sled, a ground engaging rod movable through the loop frame and provided with a longitudinally extending slot, a member mounted in the

- loop frame passing through said slot whereby the ground engaging rod may be pivoted and moved through the loop, and means for normally holding the rod out of engagement with the ground.
2. In combination, a sled, a loop frame revolvably mounted on the sled, a ground engaging rod movable through the loop frame and provided with a longitudinally extending slot, a member mounted in the loop frame passing through said slot whereby the ground engaging rod may be pivoted and moved through the loop, a spring attached at one end to the member and at the other end to the rod for normally holding the latter out of engagement with the ground.
3. In combination, a sled, a ground engaging member, means for mounting the ground engaging member so that it may be moved in and out of engagement with the ground and pivoted longitudinally and transversely of the sled, means for normally holding the member out of engagement with the ground, and means for normally holding the member in a substantially vertical position.
4. In combination, a sled, a frame rockably mounted on the sled, a ground engaging member slidably mounted in the frame and capable of pivoting in respect thereto and rocking therewith so that it may be engaged with the ground at various angles to
- the sled, means for normally holding the member out of engagement with the ground, and means for normally holding the member in a substantially vertical position.
5. In combination, a sled, a frame rockably mounted on the sled and having a bolt disposed transversely thereof, a rod having an elongated longitudinally extending slot for receiving the bolt whereby the rod is slideable and pivoted in the frame, and a spring connected to the bolt and to the bottom of the slot for normally holding the rod in a raised position.
6. In combination, a sled, a plate having an opening mounted on the sled, a ground engaging member extending through the opening of the plate, means for mounting the ground engaging member so that it may be moved in and out of engagement with the ground and pivoted longitudinally and transversely of the sled, the opening in said plate limiting the pivotal movement of said member, means for normally holding the member out of engagement with the ground, and means for normally holding the member in a substantially vertical position.

In testimony whereof I affix my signature in presence of two witnesses.

EWALD E. STURK.
